(57) **CLAIM**

What is claimed is the ornamental design for a foldable laundry basket, as shown and described.

DESCRIPTION

FIG. 1 is a perspective front view thereof, showing our new design;

FIG. 2 is a front view thereof;

FIG. 3 is a rear view thereof;

FIG. 4 is a side view thereof;

FIG. 5 is a side view thereof, which is a mirror image thereof;

FIG. 6 is a top view thereof;

FIG. 7 is a bottom view thereof;

FIG. 8 is another perspective view thereof, showing the design in a folded configuration;

FIG. 9 is a back view thereof, in a folded configuration;

FIG. 10 is a front view thereof, in a folded configuration;

FIG. 11 is a side view thereof, in a folded configuration;

FIG. 12 is a side view thereof, in a folded configuration, which is a mirror image thereof;

FIG. 13 is a top view thereof, in a folded configuration; and,

FIG. 14 is a bottom view thereof, in a folded configuration. The Broken lines illustrate portions of the design that are disclaimed and do not form part of the claimed design.
